UNITED STATES PATENT OFFICE.

LEWIS H. JOHNSON, OF BLOOMFIELD, NEW JERSEY, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

1,210,652.

Specification of Letters Patent.

Patented Jan. 2, 1917.

Application filed March 10, 1915. Serial No. 13,460.

To all whom it may concern:

Be it known that I, LEWIS H. JOHNSON, a citizen of the United States, residing at Bloomfield, in the county of Essex and State of New Jersey, have invented certain new and useful Improvements in Telephone-Exchange Systems, of which the following is a full, clear, concise, and exact description.

This invention relates to telephone exchange systems, and more particularly to such systems of the divided multiple type for use in interconnecting subscribers whose telephone lines terminate in different central offices.

The object of this invention is the provision of such a system whereby during hours of light load it is possible to dispense with the services of all operators at the trunk boards.

In accordance with one feature of this invention, a transfer circuit is provided between a trunk board and a subscribers' board at a central office, the incoming end of a trunk circuit from a distant central office during hours of light load being connected with one end of the transfer circuit. At the subscriber's board there is provided in the transfer circuit a signal which is under the control of the distant central office.

In accordance with another feature of this invention, there is associated with the circuits of such a system signal control apparatus by means of which complete supervision over a connection between two subscribers, whose telephone lines terminate at different central offices, is given to the operator at the originating central office.

This invention will be more fully understood by reference to the drawings showing one embodiment of the invention, in which all apparatus is shown in its normal and unactuated condition, and wherein—

Figure 1 shows a subscriber's line terminating at a central office, and link conductors 45 and the outgoing end of a trunk circuit at the central office; Fig. 2 shows the incoming end of the trunk circuit of Fig. 1 terminating at a trunk board at a second central office, a transfer circuit thereat for extending the trunk circuit to a subscribers' board at 50 this second central office, and the answering end of link conductors thereat; and Fig. 3 shows link conductors at the second central office and a subscriber's line terminating 55 thereat.

In the drawings there are shown subscribers' stations A and B, the lines from which terminate at central offices C and D respectively. A cord circuit E at the central office C is adapted to connect subscriber's station A with a trunk circuit F extending between a switchboard at the central office C to a trunk board at central office D. A transfer circuit G extends from the trunk board to a subscriber's board at the central office D and is adapted to connect the incoming end of the trunk circuit F with the answering end of a cord circuit H at the subscribers' board of the central office D, the calling end of the cord circuit H connecting 70 with the line of subscriber B.

It is believed that this invention will be fully understood from a description of the operation of the system shown in the drawings, and it will be so described.

Assuming that the period of light load in a central office is commencing, the plug of the trunk circuit F is inserted into jack 5 of the transfer circuit G, whereupon the trunk circuit F is extended from the trunk board 30 to the subscribers' board of central office D. Thereafter the operator at the subscribers' board handles all connections wherein trunk circuit F is involved in the same manner as the operator at the trunk board would handle such connections were the trunk circuit not connected to the transfer circuit. It will be observed that when the trunk circuit F was connected to the transfer circuit G, all apparatus associated with both circuits remained in its normal and unactuated condition.

It will now be assumed that subscriber A desires to converse with subscriber B, and it will be furthermore assumed that A has 95 signaled central office C and that the operator at C has answered and has been informed that the wanted line is that of subscriber B terminating at another central office D. The operator at C now communicates with the operator at D by means of a call wire circuit (not shown since such circuits are well understood and since it forms no part of this invention), advising the number of the wanted line and in turn is 105 advised to use trunk circuit F for this particular connection. The operator at C thereupon inserts the calling plug of cord circuit E into jack 6 of the trunk circuit F, completing a circuit from the live pole of 110

battery 7, through winding of supervisory relay 8, conductor 9, ring contacts 10 and 11 of the plug and jack, conductor 12, winding 13 of relay 14, conductor 15, tip contacts 16 and 17 of jack and plug, conductor 18 to ground. Current in this path actuates relay 14, but since winding 13 thereof is of high resistance, relay 8 which is of low resistance does not receive sufficient current to permit the operation thereof. When the above traced circuit was completed a second circuit was completed from battery 7, through conductor 20, supervisory signal 21, resistance 22, sleeve contacts 23 and 24 of plug and jack, and resistance 25 to ground, operating supervisory signal 21. When relay 14 was operated a circuit was completed from the live pole of battery 30, through resistance 31, windings 32 and 33 of relay 34, 20 sleeve contacts 35 and 36 of the jack and plug, winding of relay 37, contact 38 of relay 14, contact 39 of relay 37 and resistance 40 to ground. Current in this path actuates relay 34, but since the combined resistance 25 of resistance 31 and the windings 32 and 33 of relay 34 is high as compared to the resistance of the winding of relay 37, relay 37 is not actuated. When relay 14 was actuated a circuit for signal 41 was completed from 30 battery 42 operating this signal. The actuation of relay 34 completed a circuit from the live pole of battery 45, through signal 46, contact 47 of relay 48 and contact 49 of relay 34 to ground operating signal 46. 35 The operator at central office D observing signal 46 inserts the answering plug of cord circuit H into the jack of the transfer circuit G, completing a circuit from the live pole of battery 55, through contact 56 of relay 57, contact 58 of relay 59, resistance 60, winding of relay 61, sleeve contacts 62 and 63 of answering plug and jack, and windings 64 and 65 of relay 48 to ground. Current in this path actuates relay 48, but since 40 the resistance of relay 61 is low compared to that of the combined resistance of the windings of relay 48, relay 61 is not actuated. Relay 48 opens the circuit of signal 46 at contact 47 and by closure of its contact 66 completes a circuit from battery 42, through signal 41, winding of relay 37, sleeve contacts 36 and 35 of the plug and jack 5, winding 33 of relay 34 and contact 66 of relay 48 to ground. Current in this 45 path is sufficient to actuate relay 37 which opens its contact 39 and closes its contacts 67 and 68. The closure of contact 67 completes a circuit from battery 70 through winding of relay 71, contact 72 of relay 73, 50 contact 74 of relay 75, contact 67 of relay 37, contact 38 of relay 14, winding of relay 37, sleeve contacts 36 and 35 of plug and jack 5, winding 33 of relay 34 and contact 66 of relay 48 to ground. Current in this 55 path actuates relay 71 which opens its con-

tacts 76 and 77 and closes its contacts 78 and 79, and since the winding of relay 71 is low resistance, the signal 41 is shunted thereby, whereupon signal 41 is effaced. The closure of contact 79 of relay 71 connects a source of ringing current 80 to the ring side 81 of the trunk circuit F, but since the ring side of the connected transfer circuit G and cord circuit H is open, the ringing current at this time performs no function. 70

The operator at D after having inserted the answering plug in the jack of the transfer circuit G, inserts the calling plug of the cord circuit H into the jack of the line 80 from substation B, completing a circuit from battery 85 through signal 86, resistance 87, sleeve contacts 88 and 89 of the plug and jack and winding of cut-off relay 90 to ground, operating signal 86 and cutoff relay 90 disconnecting the limbs of the line 85 from line relay 91. The operator at D now operates key 92 connecting a source of ringing current to the called line. Signal 86 remains operated until subscriber B removes receiver from switchhook, and the operator may therefore continue to ring as long as signal 86 is operated. Upon removal of the receiver at subscriber B a circuit is completed from battery 93, through winding of 95 supervisory relay 94, contact 95 of relay 96, ring contacts 97 and 98 of plug and jack, line of subscriber B, tip contacts 99 and 100 of jack and plug and contact 101 of relay 96 to ground. Current in this path actuates relay 94, completing a circuit from battery 93, through contact 102 of relay 94, winding of 100 relay 103, resistance 87, sleeve contacts 88 and 89, and winding of cutoff relay 90 to ground. Since the resistance of relay 103 is 105 low, a low resistance shunt is placed around signal 86, effacing said signal. Current in the last traced circuit actuates relay 103, completing a low resistance path for current from the source 80. This path may be 110 traced from the source 80, through winding of relay 75, contact 79 of relay 71, conductor 81, ring contacts 104 and 105 of plug and jack 5, ring contacts 106 and 107 of jack and answering plug, contact 108 of 115 relay 61, contact 109 and winding of slow operating relay 57, contact 110 of relay 103, and contact 111 of relay 61 to ground. Sufficient current flows through relay 75 to operate it, whereupon the short circuit of relay 73 is removed, permitting relay 73 to 120 operate and lock up over a circuit from battery 120, contact 121 of relay 73, contact 67 of relay 37, contact 38 of relay 14, winding of relay 37, sleeve contacts 36 and 35 125 of the plug and jack 5, winding 33 of relay 34 and contact 66 of relay 48 to ground. Current from battery 120 to the winding of relay 73 shunts relay 71, whereupon relay 71 releases completing the talking circuit of 130

the trunk circuit F. Relay 57 was included in the above traced path from source 80 and was actuated opening its contacts 56 and 109 and closing contacts 122 and 123. The closing of contact 122 completes a circuit from battery 124, through the winding of relay 96, contact 122 and winding of relay 57, contact 110 of relay 103 and contact 111 of relay 61 to ground. The closure of contact 123 completes a circuit from battery 55, through contact 123 of relay 57, contact 125 and winding of relay 103, resistance 87, sleeve contacts 88 and 89 of the calling plug and jack and winding 90 to ground. The opening of contact 56 removes the shunt from relay 59, whereupon relay 59 is operated over a circuit from battery 126, through the winding of relay 59, resistance 60, winding of relay 61, sleeve contacts 62 and 63 of the answering plug and jack, and windings 64 and 65 of relay 48 to ground. Relay 59 in operating opens contact 58 and closes contact 127 thereby shunting the resistance 60, whereby the same resistance of the sleeve circuit is maintained. Current in the path including relay 96 operates this relay, which opens its contacts 95 and 101 and closes contacts 128 and 129, the opening of the first mentioned contacts removes the repeating coil 130 and the supervisory relay 94 from the circuit, while the closure of the contacts 128 and 129 completes a circuit from battery 140 through the winding of supervisory relay 141, contact 77 of relay 71, ring contacts 104 and 105 of plug and jack 5, ring conductor 142 of the transfer circuit G, ring contacts 106 and 107 of jack and answering plug, contact 108 of relay 61, conductor 143, contact 128 of relay 96, ring contacts 97 and 98 of calling plug and jack, line or subscriber B, tip contacts 99 and 100 of jack and calling plug, contact 129 of relay 96, conductor 144, contact 145 of relay 61, tip contacts 146 and 147 of answering plug and jack, tip conductor 148 of the transfer circuit G, tip contacts 149 and 150 of jack 5 and plug, contact 68 of relay 37, and contact 76 of relay 71 to ground. Current in this path actuates supervisory relay 141 completing a path at contact 151 of relay 141 for current from battery 7, through low resistance winding 152 of relay 14, shunting the high-resistance winding 13 thereof and permitting sufficient current to flow through the winding of supervisory relay 8 to operate this relay. The operation of relay 8 completes at its contact 153 a path through low resistance 154 shunting signal 21 thereby effacing said signal.

When the connected subscribers have completed the conversation, the receivers are restored to the switchhooks. Restoration of receiver by A permits supervisory signal 155 to operate to give a disconnect signal.

Restoration of receiver by B opens the circuit of supervisory relay 141 of the trunk circuit F, which releases, opening the circuit of the low resistance winding 152 of relay 14. Supervisory relay 8 in the cord circuit E thereupon receives less current, causing this relay to release and permit the operation of supervisory signal 21 to furnish a disconnect signal. The operator at central office C upon observing the disconnect signals 21 and 155 removes the answering and calling plugs from the jacks. The removal of the answering plug restores to normal condition the apparatus associated therewith and the line apparatus, while the removal of the calling plug restores to normal the cord circuit apparatus associated therewith and opens the circuit of winding 13 of relay 14. Relay 14 thereupon releases, opening the circuit of relay 73, and permits the establishing of the following circuits:

- (1) From battery 42, signal 41, winding of relay 37, sleeve contacts 36 and 35 of the plug and jack 5, winding 33 of relay 34 and contact 66 of relay 48 to ground.
- (2) From battery 30, through resistance 31, winding 32 of relay 34, contact 66 of relay 48 to ground.

The flow of current through the two windings of relay 34 in the direction mentioned renders the windings differential in action, whereupon relay 34 releases, opening contact 49 and closing contact 156. The closure of contact 156 completes a short circuit for the high resistance winding 65 of relay 48, thereby permitting sufficient current to flow through the winding of relay 61 to operate this relay. The operation of relay 61 opens contact 111, whereupon relays 96 and 57 release, and relay 57 in releasing opens the circuit of relay 103 which releases. The operation of relay 61 also closes contact 157 completing a circuit for supervisory signal 158, which operates to furnish a disconnect signal. The release of relay 57 removes the shunt from supervisory signal 86, which thereupon operates to furnish a disconnect signal. The operator at central office D observing disconnect signals 86 and 158, withdraws the answering and calling plugs from the jacks, permitting all apparatus to return to normal and unactuated condition.

It will be noted that by the utilization of the present invention, operators at the trunk boards may be eliminated during hours of light load; also the usual repeating coil of the cord circuit at the central office is eliminated from the completed talking circuit between two connected subscribers. Furthermore the operator at the originating central office has complete supervision over an established connection, and the operator at the second central office performs the usual duties of a trunk board operator in handling a trunked call.

It is also to be noted that the cord cir-

cuit H at central office D is arranged to function as an ordinary cord circuit in handling local calls. When the answering end of this cord circuit H is plugged into 5 the jack of a subscriber's line, marginal relay 61 operates connecting the repeating coil 130 in the circuit. In such a case relays 94, 103 and 160 control the supervisory signals 86 and 158. Also when relay 61 10 operates, relays 57, 59 and 96 are removed from the circuit and perform no function on a local call.

What is claimed is:

1. A telephone exchange system comprising a trunk circuit extending from one switchboard section to a second section, a transfer circuit connected to and extending the trunk circuit to a third section, a link circuit at the first section, a signaling device 15 for the transfer circuit located at the third section, and a relay in the trunk circuit responsive to the connection of the link circuit therewith for causing the operation of the signaling device.
2. A telephone exchange system comprising subscribers' lines terminating at a central office, a link circuit thereat, trunk and subscribers' boards at a second central office, a trunk circuit joining said first central office 20 and said trunk board, a transfer circuit connected to and extending said trunk circuit to said subscribers' board, a signal for said transfer circuit at said subscribers' board, and apparatus in said trunk circuit actuated 25 upon connection of said link circuit therewith for causing the operation of said signal.
3. A telephone exchange system comprising subscribers' lines terminating at a central office, a link circuit thereat, trunk and 30 subscribers' boards at a second central office, a trunk circuit joining said first central office and said trunk board, a transfer circuit connected to and extending said trunk circuit to said subscribers' board, a signal 35 for said transfer circuit at said subscribers' board, a control relay for said signal responsive to the connection of said link circuit with said trunk circuit to operate said signal, a link circuit at said subscribers' board, a relay associated with said transfer circuit and responsive to the connection of said second link therewith to render said signal inoperative, a subscribers' line connected to 40 the free end of each of said link circuits, supervisory signals for said first link circuit operated upon restoration of the receivers at the connected substations to furnish disconnect signals at said first central office, and 45 supervisory signals associated with said second link circuit and controlled by said control relay of said transfer circuit, said control relay being deenergized in response to the disconnection of said first link circuit 50 from said trunk circuit to cause the operation of said supervisory signals of said second link circuit to furnish disconnect signals to the operator at said subscribers' board.
4. A telephone exchange system comprising subscribers' lines terminating at a central office, a link circuit thereat, trunk and subscribers' boards at a second central office, a trunk circuit joining said first central office and said trunk board, a transfer circuit 55 connected to and extending said trunk circuit to said subscribers' board, a signal for said transfer circuit at said subscribers' board, a relay associated with said trunk circuit 60

circuit responsive to the connection of said link circuit therewith to cause the operation 65 of said signal, a link circuit at said subscribers' board, and a relay associated with said transfer circuit and responsive to the connection of said second link circuit therewith to render said signal inoperative. 70

5. A telephone exchange system comprising a telephone line terminating at a central office, trunk and subscribers' boards at a second central office, a transfer circuit joining said boards, a trunk circuit joining said first 75 central office with said trunk board and connected to said transfer circuit, a link circuit connecting said telephone line with said trunk circuit, a telephone line terminating at said subscribers' board a link circuit thereat connecting said transfer circuit with said second telephone line, disconnect signals for said first link circuit operated upon restoration of the receivers at the connected substations, and disconnect signals for said second link circuit operated when said first link circuit is disconnected from said trunk circuit. 80

6. A telephone exchange system comprising subscribers' lines terminating at a central office, a link circuit thereat, trunk and subscribers' boards at a second central office, a trunk circuit joining said first central office and said trunk board, a transfer circuit connected to and extending said trunk 90 circuit to said subscribers' board, a signal for said transfer circuit at said subscribers' board, a control relay for said signal responsive to the connection of said link circuit with said trunk circuit to operate said signal, a link circuit at said subscribers' board, a relay associated with said transfer circuit and responsive to the connection of said second link therewith to render said signal inoperative, a subscribers' line connected to 95 the free end of each of said link circuits, supervisory signals for said first link circuit operated upon restoration of the receivers at the connected substations to furnish disconnect signals at said first central office, and 100 supervisory signals associated with said second link circuit and controlled by said control relay of said transfer circuit, said control relay being deenergized in response to the disconnection of said first link circuit 105 from said trunk circuit to cause the operation of said supervisory signals of said second link circuit to furnish disconnect signals to the operator at said subscribers' board. 110

In witness whereof, I hereunto subscribe 115 my name this 9th day of March, A. D. 1915.

LEWIS H. JOHNSON.
